UNITED STATES PATENT OFFICE.

ELLSWORTH DAGGETT, OF SALT LAKE CITY, UTAH TERRITORY.

DESIGN FOR THE ORNAMENTATION OF A CRIBBAGE-BOARD.

SPECIFICATION forming part of Design No. 15,316, dated August 26, 1884.

Application filed July 2, 1884. Term of patent 7 years.

To all whom it may concern:

Be it known that I, ELLSWORTH DAGGETT, of Salt Lake City, in the county of Salt Lake, and in the Territory of Utah, have invented 5 a certain new and useful Design for Cribbage-Boards; and I do hereby declare that the following is a full, clear, and exact description thereof, reference being had to the accompanying drawings, in which—

10 Figure 1 shows a plan view of a cribbage-board ornamented in accordance with my new design; Fig. 2, a view of the same in side elevation, and Fig. 3 a view of the same in end elevation.

15 Letters of like name and kind refer to like parts in each of the figures.

The object of my invention is to provide a new design for the ornamentation of cribbage-boards; and to this end it consists in the design, as hereinafter described, and more specifically pointed out in the claims.

20 The particular shape of the board, its ends, or its sides is not an essential feature of my design, as such shape can be varied as desired.

25 In the drawings, A designates the top, B the side, and C the end, of my board. As shown, the top is of the ordinary oblong form, and is provided along its sides with the usual series of oblong blocks or divisions, A' A', in 30 which are the series of peg-holes. Within the border thus formed is an oblong space, A¹, which I ornament with my design for the top. As shown, this design consists in the representation of a series of cards spread out and 35 overlapping each other. Starting from a point near the right-hand end of space A¹, and near the central longitudinal line of the space, the cards are disposed so as to extend out around and encircle the circular space or plain 40 portion E. As shown, each successive card is so laid as to expose only a portion of the preceding card, which it overlaps. The inner edges of the cards arranged around space E are tangential to its periphery. The series 45 of cards, after encircling such space, continues in a double curve toward the opposite side and end of the space A¹. In this part of the series portions of the sides of the cards sufficient to show the nature of the spots thereon 50 are shown, each succeeding card covering up the rest of the preceding one. Gradually less

and less of the sides of the cards are displayed as the opposite end of space A¹ is approached. With the cards as arranged there is a curved band, consisting of the exposed ends of the 55 cards, crossing the space diagonally. Situated near the left-hand end of space A¹ is a card, preferably the jack of one of the suits. It is arranged longitudinally of the board, and is the only one which is displayed in full on the 60 board-top. The series of cards is at its end curved around this card, portions of the corners only being displayed, so as to show the nature of the spots thereon.

In the parts of the space A¹ not taken up 65 by the series of cards, as just described, other shorter series of overlapping cards are shown, being curved to correspond with the curvature of the adjacent portions of the main series.

70 The sides of the board, as well as the ends, are, as seen in elevation, curved inward and then outward on double or compound curves. Each side is cut away below at each end on a tangential curve, starting from the base F, and 75 connected with the straight horizontal lower line of the central part of the side by a downwardly and upwardly curved portion, G. Each side has a sunken panel, I, whose outlines correspond with those of the side. In the middle 80 of the side is shown a portion (more than half) of the five-spot of one of the suits. This card forms the first one of two similar series of overlapping cards extending therefrom in opposite directions along the side. The line of the exposed corners of these cards extends in a double 85 curve, starting downward from the upper corner of the central five-spot card and then curved upward and downward again to the bottom of the downward extension of the panel 90 end. The cards as displayed at the beginning of the series expose their sides sufficiently to show the nature of the spots thereon, the card-edges being inclined toward the middle of the panel. As the series curves downward, the 95 cards are turned so that their upper and outer corners only are shown. Other series of overlapping cards, of which only portions appear within the limit of the panel, are shown curved to correspond on their lower and inner lines 100 with the upper and outer lines of the other series. These secondary series are placed close

to the other, so as to leave only a narrow space between the two. This space, having the double curve of the main series, adds much to the ornamental appearance of the side. Each end 5 of the board is cut away below its central part, the outline of the cut being, as shown, substantially that of the ace of spades. On each end is a sunken panel, K, having the same outline as the end itself. On this panel, just above the cut-away part, is shown a card, the five-spot of one of the suits. Starting from each side of this card and curved downward is a series of overlapping cards extending to the bottom line of the panel. Each succeeding card projects beyond the preceding one sufficiently to show the spots or portions of the spots along its sides and at its outer corner. With the central fully-displayed card these series form an arch. The remaining portions of the panel 15 not covered by this arch are filled in with portions of series of overlapping cards curved on their inner sides to correspond with the curvature of the arch.

In the drawings I have shown one end and one side. On the end is shown the five of clubs and on the side the five of spades. The other side and the other end are of course to be like those shown, except that the remaining five-spots, being the five of hearts and five of diamonds, will be placed as center cards thereon, respectively.

The design as described herein and shown in the drawings constitutes a most appropriate design for cribbage-boards, and is at the same 30 time pleasing and attractive.

The term "cards," which I have used throughout my description, of course means playing-cards.

Having thus described my design, what I 40 claim is—

1. In a cribbage-board, the design which

consists in a pictorial or conventionalized representation of a pack or packs of playing-cards partially opened, as shown and described.

2. As a design for the top of a cribbage- 45 board, the representation of a series of playing-cards formed of a partially-opened pack or packs arranged on a line, the main portion of which is curved on a double curve and the ends of which are curved back upon themselves in a substantially circular curvature, and portions of partially-opened packs occupying the spaces not covered by the main series of cards, as shown and described.

3. A design for the sides of a cribbage-board, 55 consisting of the representation of a playing-card or portion thereof fully displayed at the middle of the side, and a series of overlapping playing-cards extending from each side of the central card in a double curve, at first downward, then upward, and downward again, and the portions of series of overlapping cards occupying the spaces not covered by the main series, as shown and described.

4. As a design for the end of a cribbage- 65 board, the representation of a playing-card at or near the center of the top of the end and the series of overlapping playing-cards extending downward in a curved line from each side of the central card to present the appearance of an arch, and suitable portions of partially-opened packs of cards occupying the portions of the board end not covered by the arch, as shown and described.

In testimony that I claim the foregoing I 75 have hereunto set my hand this 28th day of June, A. D. 1884.

ELLSWORTH DAGGETT.
